UNITED STATES PATENT OFFICE.

OTTO H. HUNT, OF WALLA WALLA, WASHINGTON.

SIGNAL DEVICE FOR MOTOR-VEHICLES.

1,245,593.

Specification of Letters Patent. Patented Nov. 6, 1917.

Application filed January 13, 1917. Serial No. 142,261.

To all whom it may concern:

Be it known that I, Otto H. Hunt, a citizen of the United States, residing at Walla Walla, in the county of Walla Walla, and State of Washington, have invented certain new and useful Improvements in Signal Devices for Motor-Vehicles, of which the following is a specification.

This invention relates to signal devices employed in connection with motor vehicles to indicate the fact that the driver is about to make a turn.

The invention has for its object to provide a novel and improved signal device of the kind stated characterized by a pivoted indicator adapted to be swung to extend horizontally and straight out from the side of the car, so that it is not necessary for the driver to extend one arm outward from the car when a turn or stop is about to be made, as is the usual practice. The indicator is illuminated so that the signal or warning may be given after dark.

The object stated is attained by means of a combination and arrangement of parts to be hereinafter described and claimed, and in order that the same may be better understood, reference is had to the accompanying drawing forming a part of this specification.

In the drawing—

Figure 1 is an elevation of the device; Fig. 2 is a plan view thereof; Figs. 3 and 4 are sections on the lines 3—3 and 4—4, respectively, of Fig. 1; Fig. 5 is a perspective view showing a supporting device; Fig. 6 is an elevation showing a different arrangement of the signal device, and Fig. 7 is a plan view thereof; Fig. 8 is an elevation showing another embodiment of the invention; Fig. 9 is a horizontal section on the line 9—9 of Fig. 8; Fig. 10 is a plan view of certain operating means of the indicator; Fig. 11 is an edge view of a support for said means, and Fig. 12 is a cross section of the support.

Referring specifically to the drawing, 10 denotes the side member of the windshield frame of a motor vehicle to which is attached a clamp consisting of opposite jaw members 11 and 12, respectively, which are adapted to be drawn together by a nut 13 on a bolt 14 passing through said members. The jaw member 12 has a laterally extending arm 15 formed at its outer end into a circular head or enlargement 16 having a central aperture 17 through which a bolt 18

slidably and rotatably passes. This bolt has an enlarged head 19 provided with a transverse opening through which passes the indicator, the latter being a tubular arm 20 carrying at its outer end a signal lamp. The indicator arm 20 is longitudinally adjustable in the opening in the bolt head 19 and it is held fixed in adjusted position by a set screw 24.

The bolt head 19 is located on one side of the member 16, and the other side of said member has an outstanding boss through which the bolt 18 also passes and from which it projects, the projecting end of the bolt carrying a nut or other abutment 25, between which latter and the outer end of the boss is located a spring 26, said spring being coiled around the bolt.

The inner end of the indicator arm 20 extends across that side of the member 16 on which the bolt head 19 is located and said side of the member 16 has an outstanding marginal flange 27 having two pairs of diametrically opposite recesses 28 and 29, respectively, arranged at a right angle to each other and adapted to seat the indicator arm. At diametrically opposite points the flange 27 is enlarged as shown at 30 to form stops for the indicator arm, these stops being located on one side of the recesses 28 and 29 and so positioned with respect thereto that the indicator arm can swing in one direction only from one pair of recesses to the other pair.

The supporting member 16 of the indicator arm 20, and the bolt 18 which is the pivot of said arm, are so arranged that the arm swings in a vertical plane, its normal position being alongside the windshield frame 10 and erect. To set the arm for display position, it is swung downward to extend horizontally and outward from the side of the car. As each side of the car will be equipped with one of the indicators, the direction in which the car is to make a turn will be indicated by projecting the indicator on that side toward which the turn is to be made.

When the indicator arm 20 is in erect position, its inner end seats in the vertically spaced recesses 28, and when it is in horizontal display position, its inner end seats in the horizontally spaced recesses 29. In both positions the arm abuts against the stops 30, these being so located that the arm can swing through an arc of ninety degrees.

only between its erect and horizontal positions.

The bolt head 19 has a projecting handle 31 whereby the bolt 18 is turned to swing 5 the indicator arm 20 as hereinbefore described. The spring 26 permits the bolt 18 to yield sufficiently to allow the indicator arm to rise out of the recesses 28 and 29 and pass along the edge of the flange 27 in its 10 travel from one pair of said recesses to the other pair. The spring firmly holds the arms seated in the recesses and prevents all looseness and rattling of the parts.

The signal lamp carried by the outer end 15 of the indicator arm 20 comprises an ordinary incandescent electric lamp 32 inclosed in an annular housing 33 having front and rear lenses 34 inscribed with a suitable legend as shown, or left plain. The outer 20 end of the indicator arm is connected to the lamp housing by a screw joint or any other suitable connection, the extremity of the arm extending into the housing and carrying a standard socket 35 for the 25 lamp 32.

The indicator arm 20 is hollow so that the circuit wires 36 of the lamp 32 may be passed therethrough, and at the inner end of the arm is a switch for controlling the 30 lamp circuit, said switch being constructed and arranged to close the lamp circuit when the arm is swung down into display position, and to break the lamp circuit when the arm is returned to its upright inoperative position. This switch mechanism 35 comprises the following parts:

The wires 36 run through the indicator arm 20 and pass through a ball 37 of insulation fastened to the inner end of the 40 arm. The part 37 carries two spaced switch terminals 38 so positioned that they come in contact with and are bridged by a switch tongue 39 fixed on the member 16, whereby the lamp circuit is closed, this action taking 45 place when the arm is swung down to display position. When the arm is swung up into inoperative position, the terminals 38 leave the switch tongue 39, and the lamp circuit is thus broken. The current for the 50 lamp may be taken from any suitable source, and a switch will also be provided for entirely cutting out the lamp circuit in the daytime.

The device is shown attached to the wind- 55 shield frame, but if this frame is out of convenient reach of the driver, the supporting post shown at 40 in Fig. 5 may be provided, said post being fastened to the car body at any convenient place.

Figs. 6 and 7 show a slightly different arrangement of the device, the same being 60 mounted to swing in a horizontal plane, the supporting member 16 being positioned accordingly, and being provided with a bracket 65 arm 41 for attachment to the side of the car.

In each embodiment of the invention a flat plate, shown dotted at 42, may be fixed to the indicator arm 20 to make the signal more effective and easily visible.

Figs. 8 to 12 show another embodiment of the invention. Here, the signal is operated from a distance, as the dash 43 of the car. The windshield frame 10 carries a clamp 44 having an outstanding arm 45 formed at its outer end with a bearing 46 in which is 75 journaled a spindle 47 projecting from the ends of the bearing, and having one of its ends formed with a spherical head 48, and its other being screw threaded to receive a nut 49. Next to the bearing, the 80 first-mentioned end of the spindle is also formed with an outstanding annular shoulder 50 between which and the bearing is mounted a spring washer 51 to prevent rattling of the parts. The other end of the 85 spindle has a squared portion 52 on which is mounted a rocker arm 53, the same being held on the spindle between the bearing 46 and the nut 49. An indicator arm 54 similar to the arm 20 hereinbefore described is connected to the head 48, the connection being made by screwing the inner end of the arm 90 into the head.

On the dash 43 is mounted a support for a hand lever 55 which is connected by a rod 95 56 with the rocker arm 53, whereby the indicator arm 54 is swung into and out of display position.

The support for the hand lever 55 is a circular base plate 57 fixed to the dash 43 by 100 screws 58 or other means, and having a central aperture to receive a pivot bolt 59 on which the hand lever is mounted, said lever being retained on the bolt by a nut 60 screwed thereon, with a spring 61 between 105 the nut and the lever to prevent rattling. One end of the lever is formed with a handle, and to its other end is connected the rod 56. The outer face of the base member 57 across which the lever swings has an outstanding annular flange 62 provided with a locking notch 63 in which the lever seats when it is swung to place the indicator in 110 display position. The lever is free to move along the bolt 59 to enter and leave the notch 63, and the spring 61 holds it firmly seated in the notch to prevent looseness and rattling. A locking notch 64 for holding the lever at the limit of its other movement, is 115 also provided.

The indicator arm 54 carries a lamp 65 as before, and the movement of the lever 55 controls the circuit of the lamp through the 120 following switch mechanism:

The base member 57 has a projecting arm 125 66 which carries two switch contacts 67 insulated from the arm as shown at 68, and having suitable connections with the conductors of the lamp circuit. To the lever 55 is fastened a switch blade 69, the contacts 67 130

being so positioned that they are engaged by the switch blade when the lever is swung to set the indicator, thus closing the lamp circuit. When the lever is swung to restore the 5 indicator to inoperative position, the switch blade leaves the contacts, whereupon the lamp circuit is broken.

I claim:

1. A direction signal for motor vehicles, comprising an indicator arm mounted at the 10 side of the vehicle and adapted to be swung in a vertical plane to project outward therefrom, a rotatable member having a head provided with a transverse aperture through 15 which the inner end of the indicator arm passes and in which it is longitudinally adjustable, means for locking the indicator in adjusted position to said member, a support for the rotatable member, and means for attaching the support to the vehicle.
2. A direction signal for motor vehicles, comprising an indicator arm mounted at the 20 side of the vehicle and adapted to be swung in a vertical plane to project outward therefrom, a rotatable member carrying the indicator arm, said arm being adjustable in the direction of its length, means for locking the indicator in adjusted position to said member, a support for the rotatable member, and 25 means for attaching the support to the vehicle.

3. A direction signal for motor vehicles, comprising an indicator arm mounted at the side of the vehicle and adapted to be swung to project outward therefrom, a rotatable 35 and slidale member, a support for said member from which it projects, the indicator arm passing through one of the projecting ends of the member, an abutment on the other projecting end of the member, a spring 40 between said abutment and the support, the side of the support from which the first-mentioned end of the member projects having recesses in which the inner end of the arm seats at the limits of its movements, and 45 stops for the arm alongside the recesses.

4. A direction signal for motor vehicles, comprising a pivoted indicator arm mounted at the side of the vehicle and adapted to be swung in a vertical plane to project outward 50 therefrom, a rotatable and slidale member operatively connected to said arm and having a laterally projecting part, a support for said member having a projecting end flange provided with recesses in which the aforesaid projecting part seats to limit the rotary movement of the aforesaid member, and a 55 spring engageable with said member for yieldingly holding the same seated in the recesses.

In testimony whereof I affix my signature.
OTTO H. HUNT.
